Inventor

UNITED STATES PATENT OFFICE.

EDWIN BALL STIMPSON, OF BROOKLYN, NEW YORK.

CARTRIDGE-BELT.

1,288,263.

Specification of Letters Patent. Patented Dec. 17, 1918.

Application filed June 4, 1918. Serial No. 238,089.

To all whom it may concern:

Be it known that I, EDWIN BALL STIMPSON, a citizen of the United States, residing in Brooklyn, county of Kings, and State of New York, have invented a certain new and useful Improvement in Cartridge-Belts, of which the following is a specification.

This invention relates generally to machine gun cartridge feeding belts.

10 In application Ser. No. 238,553, filed May 9, 1918, a cartridge belt construction is shown and described in which comparatively unsubstantial sheet material, such as paper, is reinforced by having longitudinally arranged cords embedded therein, strips of such reinforced material being attached to each other to form cartridge holding loops by stitching the reinforced portions of the strips to each other at the proper 15 intervals. This provides a very effective and simple construction but I have found that it is possible to still further simplify the structure by utilizing the longitudinally arranged cords not only for the reinforcing function, but also as the thread members by means of which the strips are attached together to form the cartridge holding loops. Accordingly the main object of the present invention is to provide a simple and substantial cartridge belt construction of the general type referred to.

With this and other objects in view, one feature of the invention consists in forming a cartridge belt of layers of sheet material having reinforcing cords arranged longitudinally thereof, and in utilizing the reinforcing cords as means for stitching the layers of material together at intervals to form cartridge holding loops.

40 Another feature of the invention consists in interposing spacing members between the layers of material forming the loops at the points where the layers are stitched together.

Other features of the invention will be hereinafter referred to.

In the drawings, in which a number of preferred embodiments of the invention are illustrated,

50 Figure 1 is a side view of a section of cartridge belt embodying the invention and showing the appearance of the belt at the end of the reinforcing and stitching operation.

Fig. 2 is a vertical sectional view of the section of belt shown in Fig. 1.

55

Fig. 3 is a side view of a section of a completed belt.

Fig. 4 is a sectional view of the structure shown in Fig. 3.

Fig. 5 is a diagrammatic view showing 60 on an enlarged scale the relation of the reinforcing cords and the strips of material making up the belt.

Fig. 6 is a sectional view of a modified form of belt in which four separate strips 65 of material are employed in making up the belt.

Fig. 7 is a view similar to Fig. 6 showing 70 a form of belt in which three strips of material are used, one of which is folded along the central portion to form covering layers on both sides of the belt proper.

Fig. 8 is a perspective view of a spacing member that may be used as part of the belt structure.

75

Fig. 9 is a diagrammatic view similar to Fig. 5 and showing the manner in which the spacing member is used in making up the belt.

In Figs. 1, 2, 3, and 4 of the drawings 80 there is shown a section of a partially and a fully completed belt made up of two strips of sheet material which are attached together at suitable intervals along the central portion and along one edge to form cartridge holding loops. The thread or cord members which are employed for stitching the cartridge engaging portions 1 and 3 of the strips of material together, as at the points 7 of Fig. 1, are preferably of substantial size and strength in order that the straight line stretches 5 intervening between adjacent stitched portions 7 may be enabled to serve as reinforcing tensile members for the belt, thereby permitting the use of sheet 85 material such as paper or light and thin fabric having a low degree of tensile strength.

While two single strips of material having the width of the portions indicated at 1 and 3, or even a single strip folded over into two layers, may be used to form the belt, I preferably employ two strips of the width indicated in Figs. 1 and 2 and which are folded over on themselves at 6, as shown in Fig. 4, 100 to form the belt. The folded over portions 105

2 and 4 may be attached in place on the outer faces of the portions 1 and 3 in covering relation to the cords 5 by means of any suitable adhesive, so that the completed belt 5 will appear as in Figs. 3 and 4.

It will be obvious that other arrangements of the sheet material into suitable layers to form a belt may be had and two modifications of this nature are shown in 10 Figs. 6 and 7 of the drawing. In the modification shown in Fig. 6, four separate strips of paper are employed, the inner cartridge engaging strips 1 and 3 being preferably formed of heavier stock than that comprising 15 the outer or cord covering layers 25 and 27. In Fig. 7 the outer covering layers 21 are preferably formed of a single strip of double width and doubled over at 23 into position. The paper strip 21 being comparatively 20 thin is readily pierced by the pointed bullets as the cartridges 10 are passed into place within the loops provided in the belt.

It will be seen in Fig. 1 that a greater 25 number of stitches are provided in the stitched portions that are to form the loops for receiving the smaller end 12 of the cartridges than at the other edge of the belt.

In Fig. 5 of the drawing there is shown in 30 an enlarged diagrammatic view the relative arrangement of a pair of oppositely disposed cords 5 and the intervening belt strips 1 and 3. It will be seen that the cords 5 are arranged in a stitched formation at 7 to thereby attach the strips 1 and 3 together at suitable intervals to form cartridge holding loops.

In Fig. 8 of the drawing is shown a spacing member 17 adapted to be inserted between 40 the belt strips at the points where the strips are stitched together so as to minimize the extent to which the walls of the belt must be deflected to embrace the cartridges when they are put into place in the loops. The spacing members 17 are preferably formed with enlargements 19 at one end that fit into the narrowed portions of the adjacent cartridges at the shoulders thereof.

In Fig. 9 of the drawing the relation of the 50 strips 1—3, the cords 5 and stitches 7, and the enlarged ends 19 of the spacing members 17, to each other is clearly shown. The spacing members are made of such material, as for example, cardboard, that the cord members can be passed therethrough to form the stitches.

Having thus described my invention, what I claim and desire to secure by Letters Patent of the United States is:

60 1. A cartridge belt formed of layers of sheet material and having reinforcing cords arranged longitudinally thereof, said rein-

forcing cords being also arranged in an interengaged relation to stitch the layers of material together at intervals to form cartridge holding loops. 65

2. A cartridge belt formed of layers of paper and having oppositely disposed reinforcing cords arranged longitudinally thereof, said oppositely disposed cords being arranged in an interlocked relation to stitch the layers of paper together at suitable intervals to form cartridge holding loops. 70

3. A cartridge belt formed of strips of sheet material and having reinforcing tensile members arranged opposite each other along the lateral margins thereof, said oppositely disposed tensile members being interengaged at intervals in a locked stitch arrangement to attach the interposed strips together to form cartridge holding loops. 75

4. A cartridge belt formed of layers of sheet material and having oppositely disposed reinforcing cords arranged longitudinally along the opposite outer faces thereof, said reinforcing cords being also utilized to stitch the intermediate layers of material together to form cartridge holding loops, and further layers of material arranged in covering relation to said cords. 85

5. A cartridge belt formed of layers of sheet material and having oppositely disposed reinforcing cords arranged longitudinally along the lateral edges of said layers, and said reinforcing cords being also utilized to stitch the layers of material together at intervals to form cartridge holding loops, a greater number of stitches being employed in the stitched portions along one edge than the other to thereby form loops of reduced diameter to fit the smaller end of the cartridges. 95

6. A cartridge belt formed of layers of sheet material and having reinforcing cords arranged longitudinally thereof, spacing members inserted between said strips at suitable intervals to form cartridge holding loops, and said reinforcing cords being utilized to stitch said strips and said spacing members together. 105

7. A cartridge belt formed of layers of sheet material and having reinforcing cords arranged longitudinally along the outer faces thereof, spacing members inserted between said strips at suitable intervals to 115 form cartridge holding loops, said reinforcing cords being utilized to stitch said strips and said spacing members together, and further layers of material arranged in covering relation to said cords. 120

Signed at Brooklyn, in the county of Kings, and State of New York, this 28th day of May, 1918.

EDWIN BALL STIMPSON.
